(57) **CLAIM**

The ornamental design for a self-massaging device, as shown and described.

DESCRIPTION

FIG. 1 is a top front perspective view of a self-massaging device;

FIG. 2 is a right elevation view thereof;

FIG. 3 is a left elevation view thereof;

FIG. 4 is a top plan view thereof, the bottom plan view being a mirror image thereof;

FIG. 5 is a front elevation view thereof;

FIG. 6 is a rear elevation view thereof; and,

FIG. 7 is a perspective view thereof, shown in use.

The broken lines shown in the drawings illustrate portions of the self-massaging device that form no part of the claimed design.

The cutaway symbols illustrated in break lines in the drawings indicate a symbolic break in the length of the design for the self-massaging device indicating an indeterminate length. The appearance of any portion of the article between the break lines forms no part of the claimed design.
